UNITED STATES PATENT OFFICE.

HENRIK HILLBOM, OF WALLINGFORD, CONNECTICUT, ASSIGNOR TO R. WALLACE & SONS MFG. CO., OF WALLINGFORD, CONNECTICUT, A CORPORATION.

DESIGN FOR A TEA OR COFFEE POT OR SIMILAR ARTICLE.

43,219.

Specification for Design.

Patented Nov. 5, 1912.

Application filed August 29, 1912. Serial No. 717,793. Term of patent 14 years.

To all whom it may concern.

Be it known that I, HENRIK HILLBOM, a citizen of the United States, residing at Wallingford, in the county of New Haven and State of Connecticut, have invented a new, original, and ornamental Design for a Tea or Coffee Pot or Similar Article; and I do hereby declare the accompanying drawing to be a full, clear, and exact illustration of the same, and which said drawing constitutes part of this application and represents a side view of a coffee pot embodying my design.

I claim:

The ornamental design for a tea or coffee pot or similar article, as shown.

HENRIK HILLBOM.

Witnesses:

FLOYD WALLACE,
HENRY L. WALLACE.
